UNITED STATES PATENT OFFICE.

GEORGE J. WEBER, OF KANSAS CITY, MISSOURI.

PROCESS OF PRODUCING GAS AND POWER.

No. 890,475.

Specification of Letters Patent.

Patented June 9, 1908.

Application filed April 25, 1903, Serial No. 154,864. Renewed October 28, 1907. Serial No. 399,396.

To all whom it may concern:

Be it known that I, GEORGE J. WEBER, a citizen of the United States of America, residing in Kansas City, in the county of Jackson and State of Missouri, have invented a new and useful Improvement in Process of Producing Gas and Power, of which the following is a specification, reference being had therein to the accompanying drawings, forming a part thereof.

My invention relates to an improved process for producing gas and power.

My invention relates particularly to processes in which a gas engine is employed in connection with a producer to produce gas which is exploded in the gas engine to produce power.

My invention has for its object the conservation of heat produced in the manufacture of the gas and from the explosions of the gas in the engine.

My invention broadly stated consists in employing a gas engine to suck air and steam through burning fuel, thereby producing combustible gas, employing the gas prior to washing, and while it retains a large amount of heat to generate steam which is used for making the gas, then washing the gas and exploding the gas in the engine, whereby power is produced by which the process is continued.

Other novel features are hereinafter fully described and claimed.

In the accompanying drawings illustrative of my invention, Figure 1 is a view, partly in elevation and partly in vertical section, of an apparatus by means of which my new process is carried into effect. Fig. 2 is a horizontal sectional view taken on the dotted line *a*—*b* of Fig. 1. Fig. 3 is a longitudinal vertical sectional view of the check valve between the engine and the scrubbing chamber.

Similar characters of reference indicate similar parts.

The generating chamber 1 comprises a vertical tubular shell lined inside above the transverse grate 3 with a fire brick lining 2. 4 denotes the fuel resting upon the grate. A feed opening 5 is provided in the top of the chamber 1. A removable closure 6 is provided for the feed opening 5. In the top of the chamber 1 is provided a peep opening 7 through which the condition of the fire may be observed. A closure 8 is provided for the

peep opening. In opposite sides of the chamber 1 below the grate 3 are two doors 9 through which ashes may be removed. In each door is provided an air inlet having a closure 10. Below the gate 3 is provided also another air inlet 11 through which air may be driven into the chamber 1 by means of a blower 12. A slideable door 13 is mounted on the outside of the chamber 1 for closing the inlet 11. A vertical boiler 14, adjacent to the chamber 1, is provided with two transverse partitions 15, which form between them a steam space through which extend one or more vertical tubes 16, which receive gaseous products from combustion chamber 1 and serve to generate steam from water held in the steam space in the boiler. The upper end of a pipe 17 is connected with the said steam space at a point above the water level, and extends therefrom into the combustion chamber, thence downward through the fire brick to a point below the grate 3 where the steam is discharged. The boiler 14 below the lower partition 15 is provided with a gas inlet 18 connecting with the gas outlet 19, which extends through the brick lining and the wall of the chamber 1 above the grate 3.

In the inlet 18 of the boiler 14 is pivotally mounted an inwardly swinging flap valve 20 which prevents back flow of the gas passing through the inlet 18 and also prevents back firing into the combustion chamber 1 from the engine. The valve 20 further serves as a baffle plate to deflect downward to the bottom of the boiler sediment or brands entering through the inlet 18. An outlet for the escape of gas is provided in the boiler 14 above the upper partition 15. This outlet, denoted by 21, is to permit the escape of gas when starting the fire in the generating chamber or when it is desired to shut down the engine. A rotary valve 22 normally closes the outlet 21. In the boiler 14 below the valve 20 is provided a sediment outlet 23 normally closed by a rotary hollow valve 24, one side of which is provided with a hole 25 adapted to register with the outlet 23, and adapted, when in position shown in Fig. 1 to receive sediment from the boiler 14. By rotating the valve half around, the sediment collected therein may be dropped out of the boiler without permitting gas to escape.

26 indicates a washing and cooling cham-

ber adapted to contain water. Water is admitted through an opening 27 in the top of the chamber, a rotary valve 28, normally closing said opening. In the lower end of chamber 26 is provided an outlet 29 in which is rotatably mounted a rotary valve 30, similar in construction and operation to valve 24 and provided with a side opening 31 adapted to register with the outlet opening 29 so as to receive sediment therethrough. By rotating the valve 30 half around, the sediment may be dropped out without permitting escape of water from the chamber 26.

32 denotes a pipe the upper end of which connects with the boiler 14 above the upper partition 15, the lower end of the pipe extending into the chamber 26 below the level of the water held herein.

33 is the scrubbing chamber provided with means for holding in the bottom thereof a supply of water below the level of which extends the lower end of a pipe 34, which extends through the side of the chamber 33 and upwardly into the chamber 26 above the level of the water in chamber 26. A transverse perforated partition 36 is provided in chamber 33 above the water therein, and upon the said partition is placed a supply of carbonaceous particles 37, preferably coke.

30 Another transverse partition 38 is provided in chamber 33 above the coke, and has resting upon it a quantity of shavings 39. A vessel 40 disposed lower than chamber 33 and provided with an open top is adapted to contain water. A pipe 41 connected at its upper end with the chamber 33 extends into the vessel 40 below the level of the water therein. This pipe serves to keep the water in chamber 33 at a given height, and with the water 40 in vessel 40 serves as a water seal to prevent the escape of gas from chamber 33. Water for spraying the shavings and coke in chamber 33 is supplied through an inlet 42 in the top of chamber 33, the inlet being normally

45 closed by a rotary valve 43. In the cylinder 44 of an ordinary gas engine is mounted the piston 45. At one end of the cylinder is the explosion chamber 46. A valve 47 normally closes the opening connecting the explosion 50 chamber 46 with the mixing chamber 48 provided with an air inlet 49. A conductor 50 connects the mixing chamber with the upper end of the scrubbing chamber 33. In the said conductor and forming a part thereof is a check 55 valve, shown in section in Fig. 3, comprising a casing 51 in which is pivotally mounted a flap valve 51', which opens toward the mixing chamber. This valve prevents back firing from the engine through conductor 50.

60 In the conductor 50 is inserted also a throttle valve 52 of ordinary construction. By means of this valve the gas may be shut off. Between the throttle valve 52 and the mixing chamber, the conductor 50 is provided with a

try cock 53, of ordinary construction, the function of which is to enable the operator to determine when combustible gas is passing through the conductor 50.

The cylinder 44 is provided with the ordinary water jacket, the numeral 54 indicating the water space thereof. A pipe 55 is connected at its lower end to the said space and at its upper end with the steam space provided in a vertical boiler 56, the said steam space being formed by providing two transverse partitions 57 in the boiler. The function of the pipe 55 is to supply hot water to the boiler 56. Through the partitions 57 extend one or more vertical tubes 58 which serve to convey exhaust gas from the engine cylinder adjacent to the water in the steam space of boiler 56. The steam spaces of boilers 14 and 56 are connected above the water level of each boiler by a horizontal pipe 59 which serves to convey steam from boiler 56 to the combustion chamber through pipe 17. To the boiler 56 below the lower partition 57 is connected the upper end of a pipe 60 the lower end of which connects with a chamber 61, which is connected with the exhaust chamber 62 by an opening normally closed by an exhaust valve 63.

64 and 65 denote respectively the ports connecting the cylinder 44 with the exhaust and explosion chambers. Ignition of the charge in the explosion chamber 46 may be obtained in any of the well known ways.

66 and 67 denote two electrodes in the explosion chamber between which an electric spark may be caused to pass for producing the explosion of the charge. The proportioning of the movement of the valves 47 and 63 and the passing of the spark between electrodes 66 and 67 may be controlled by the running of the engine in the ordinary manner.

The boiler 56 is provided above the upper partition 57 with an outlet for the exhaust gas passing through the tubes 58. This outlet is indicated by 68.

69 denotes a cock in the pipe 55 connected by a pipe 70 with the water supply tank, not shown, by which the boiler 56 is supplied with water. 71 indicates another pipe connecting the lower side of the water jacket with the said water supply tank.

72 denotes a removable closure for an opening in the lower end of the side of the chamber 33 designed for the removal of dirt from the chamber 33. Between the two horizontal planes in which are located the ends of the pipes 32 and 34, the side wall of the chamber 26 is provided with a try cock 73 by means of which it may be determined when the water in the chamber is at the proper level.

In operating my invention, water is first

supplied to the boilers 14 and 56, and chambers 26 and 33, after which the valve 22 and door 13 are opened, the other valves and doors being closed, excepting closure 6 which 5 is removed for inserting the fuel into the generating chamber. The charcoal 4 is then ignited, closure 6 replaced, and the blower 12 started. The air passing through the charcoal continues the combustion thereof the 10 gaseous products passing into the boiler 14 through the outlet 19 and inlet 18 past the flap valve 20, thence through the tubes 16 to and through the outlet 21. When the generating chamber has become sufficiently 15 heated and steam formed in the steam space in boiler 14 the valve 22 is closed. The steam generated in the boiler 14 passes by pipe 17 into the lower end of generating chamber 1 and uniting with the incoming air 20 assists in the combustion of the charcoal, thus forming products of combustion which pass from the generating chamber into and through boiler 14 and into the pipe 32 from which the products pass into and through the 25 water in chamber 26 where the gaseous products are washed and cooled. The cooled gases then pass by pipe 34 into and through the water in the lower end of chamber 33 where they are further washed and cooled, 30 passing then through partitions 36 and 38, coke 37, and shavings 39 by means of which the gaseous products are thoroughly scrubbed and purified and are in the form of combustible gas. The coke and shavings are 35 kept moistened by water admitted through the inlet 42. The throttle valve 52 then being opened, the gas will pass through conductor 50, valve casing 51, past the flap valve 51', through throttle valve 52 and into 40 the mixing chamber 48. By opening the try cock 53 and applying a flame to the gas issuing therefrom, it can be determined when the gas is combustible. When the gas will 45 ignite, it is ready to be used in running the engine. The door 13 is then closed, the blower 12 stopped and the closure 10 opened to admit air into the generating chamber. The engine is then started manually and caused to draw a charge of mixed gas and air 50 from the mixing chamber past valve 47 into the explosion chamber 46 where the charge is exploded by a spark passing between the electrodes 66 and 67. The exploded charge then passes by port 65 into the cylinder 44 where the charge is used to actuate the reciprocation of the piston 45, thus converting the gaseous products into mechanical energy. The piston in moving in the proper direction causes a partial vacuum to be formed in the 55 cylinder 44, explosion chambers 46, mixing chamber 48, conductor 50, chamber 33, chamber 26, and boiler 14 and connecting pipes, thus causing air to be drawn into the generating chamber, and the gaseous prod-

ucts to pass from the combustion chamber 65 into the engine cylinder where they are converted into mechanical energy, a portion of which is used, as described, for continuing the process.

As the exhaust gases pass from the engine 70 cylinder 44 through port 64, exhaust chambers 61 and 62, pipe 60, and tubes 58, the water in the steam space in boiler 56 becomes generated into steam which passes by means of pipe 59, boiler 14 and pipe 17 into 75 the generating chamber, as already described. At the same time the water in the water jacket space 54 becomes heated and passes by pipe 55 into the water space in boiler 56, thus continuing the supply of hot 80 water therein and assisting the exhaust gases in generating steam in the boiler 56.

In using charcoal as a fuel for the production of combustible gas no difficulty is experienced by the formation of cinders or clinkers in the generating chamber. Bridging or running together of the fuel, thus affecting the draft and supply of gaseous products, a trouble commonly experienced when coke or coal is used, is perfectly eliminated by the 90 use of charcoal. Gummy or tarry substances in the gas produced from mineral substances, such as coke, coal, or mineral oils, are avoided by using charcoal as the fuel, and the gas produced is free from grit 95 and undue wear of the piston and valves of the engine propelled by the gas is thus avoided. Charcoal being usually produced from wood, which is generally plentiful, and readily made by unskilled labor, combustible 100 gas and power can be produced very economically by my process. Charcoal being very light can also be readily and cheaply transported over mountainous countries or other places and thus becomes a very desirable fuel from which power can be obtained. Charcoal being free from sulfur and other substances which make coal, coke or oils objectionable makes it a very cheap and efficient source of power. 110

In the carrying out of my process the retracting of the piston of the engine creates in the producer chamber a partial vacuum due to suction by the movement of the piston in the cylinder. This suction draws out 115 a portion of the gases occluded in the porous charcoal, which withdrawn gas is replaced by incoming air and steam, thus effecting a more intimate and thorough contact of the air and steam with the charcoal and producing a richer gas than would be effected by forcing the steam and air through the charcoal without first having subjected the fuel to the vacuum forming action. If the steam and air were forced through the fuel without 120 action of the suction effect, the pores of the charcoal would be filled with gas which would not be replaced by the steam and air 125

passing through, and the steam and air would pass around the outsides of the particles of charcoal and thus would not be exposed to as much incandescent carbon, the gas produced thereby being of a poorer quality. Furthermore by the reciprocation of the engine piston the suction is effected in a series of impulses, the result of which is to lift up the light charcoal with each retraction of the piston, after which it is dropped. This alternate lifting and dropping of the charcoal prevents any packing effect and permits a plentiful supply of air and steam being drawn in at each inspiration. Charcoal being light can be lifted in this manner by the suction of the engine, but it is not light enough to be drawn like dust out of the producer chamber. Besides owing to its porosity charcoal can absorb a vast amount more of the air and steam than any other fuel, and when it is dropped it will not pack. Another advantage of its use is due to its even texture and lack of resinous, tarry sulfurous or other impure ingredients. Therefore owing to the several features noted, the absence of bridging, due to running together, or the formation of cinders which bridge over the chamber and close the passage for air and steam, the suction effect which withdraws the larger part of gas absorbed in the pores, thus permitting each intake of air and steam to fill the pores, and the alternate lifting and dropping of the charcoal with each impulse of the engine piston, the applicant is enabled to produce in a simple manner from a cheap fuel a combustible gas always uniform in composition and hence requiring no regulation of the volume of air mixed with it for exploding in the engine. Then as charcoal does not bridge over or make clinkers in the producer it requires no operator expert for the purpose for running the apparatus, such as is required when other fuels are used to produce gas at all regular. Stoppage of the running of the apparatus for the purpose of breaking up clinkery masses in the chamber is also avoided, and an unskilled operator may run the apparatus day after day without further attention than to supply fuel to the producer.

In the use of my process all grades of fineness in charcoal may be used, and I have been enabled to produce a uniform composition of good combustible gas from the slack or waste residue found in charcoal kilns and heretofore thrown away. In the manufacture of charcoal there collects in the bottom of the kiln very fine particles or waste that has been deemed of no value and has been thrown away. By the use of my process this waste material can be used to produce a quality of gas with as much uniformity of composition and as cheaply as with the use

of the merchantable product of the charcoal kiln.

65

For the process of producing gas from charcoal and for the process of producing gas from the waste products of the charcoal kiln and converting the same into power I am about to file other applications for Letters 70 Patent.

70

Having thus described my invention, what I claim and desire to secure by Letters Patent is:

1. The process consisting in passing air and steam through burning fuel, washing the resulting gaseous products, mixing air with said products, exploding the mixture in an engine, utilizing the heat of such explosion and the heat derived from the gaseous products prior to their washing for generating steam used with the air in burning the fuel, and utilizing power derived from such explosion for drawing the steam and air through the fuel.

85

2. The process consisting in passing air and steam upwardly through burning fuel, passing the resulting gaseous products through water, mixing air with the washed products, exploding the mixture in an engine, utilizing the heat of such explosion and the heat derived from the gaseous products prior to their passing through water for generating the steam so used, and utilizing the power of such explosion for drawing the steam and air through the fuel.

90

3. The process consisting in passing air and steam through burning fuel, washing and scrubbing the resulting gaseous products, mixing air with the said products, exploding the mixture in an engine, utilizing the heat of such explosion and the heat derived from the gaseous products prior to their washing for generating the steam so used, and utilizing the power of such explosion for drawing the air and steam through the fuel.

100

4. The process consisting in drawing air and steam by suction upwardly through burning fuel in a series of impulses, washing and scrubbing the resulting gaseous products, mixing air with said products, exploding the mixture, and utilizing the heat of such explosion and the heat derived from the gaseous products prior to their washing for generating the steam so used.

105

5. The process consisting in passing air and steam upwardly through burning fuel in a series of impulses, washing and scrubbing the resulting gaseous products, mixing air with the washed and scrubbed products, exploding the mixture, utilizing the heat of such explosion and the heat derived from the gaseous products prior to their washing for generating the steam so used, and utilizing the power of such explosion for drawing the steam and air through the burning fuel.

115

120

125

6. The process consisting in forcing air and steam through burning fuel, washing the resulting gaseous products, exploding said products to produce power, utilizing the heat of the exploded gaseous products and the heat derived from the gaseous products, prior to their washing, for generating the steam used for producing said gaseous products.

In testimony whereof I have signed my name to this specification in presence of two 10 subscribing witnesses.

GEORGE J. WEBER.
